AUTOMATIC FEED MECHANISM FOR
GRINDING MACHINES

Ivor J. Gruenberg, Pleasant Ridge, and Reino H. Mustonen, Detroit, Mich., assignors to The Gear Grinding Machine Company, Hamtramck, Mich., a corporation of Michigan

Application August 12, 1946, Serial No. 690,024

8 Claims. (Cl. 51—52)

1

The invention relates to automatic feed mechanisms for grinding machines and more particularly to grinding machines of the type used in the grinding of gears with formed grinder wheels.

It is the object of the invention to obtain a construction which is applicable to any grinding machine and functions to automatically advance the grinder wheel into the work in successive steps.

It is a further object to accurately control this advancement so that the successive steps thereof are neither too large nor too small and will terminate when the work is of finished size.

It is a further object to obtain a construction which does not in any way interfere with the manual adjustment of the grinder wheel into or out of operative relation to the work.

It is a further object to utilize certain elements of this manually operable adjustment mechanism as essential elements of the automatic feed. With these and other objects in view the invention consists in the construction as hereinafter set forth.

In the drawings:

Fig. 1 is a front elevation of a grinding machine to which my automatic feed mechanism is applied;

Fig. 2 is a plan view of a portion of the machine;

Fig. 3 is an elevation similar to Fig. 1 illustrating only the automatic feed mechanism and being partly in section;

Fig. 4 is a vertical central section on line 4—4, Fig. 3, illustrating the step by step automatic feed mechanism;

Fig. 5 is a section on line 5—5, Fig. 4;

Fig. 6 is a vertical central section through the metering means and on line 6—6, Fig. 2;

Fig. 7 is a plan view of Fig. 6;

Fig. 8 is an elevation of the construction shown in Fig. 4 viewed from the right end thereof;

Fig. 9 is a diagrammatic view illustrating the hydraulic operating system;

Fig. 10 is a section substantially on line 10—10, Fig. 9, illustrating the locking valve for the hydraulic operation mechanism.

While the automatic feed mechanism is applicable to various types of grinding machines, it is specifically shown in connection with a machine designed for the grinding of gears. Generally described, this machine comprises a bed member A on a portion of which is mounted a work support including a head stock B and tail stock B' having centers B² for engaging an arbor

2

on which the gear to be ground is mounted. There is also an indexing mechanism B³ (not shown in detail) for periodically rotating the arbor step by step. On another portion of the bed A is mounted for longitudinal reciprocation a table C. This table carries a grinder wheel D which is mounted on a head E vertically adjustably secured to a column F. As the specific construction of this grinder wheel mounting is not a part of the instant invention, it will be sufficient to describe the means employed for manually vertically adjusting the head E on the column F so as to move the grinder wheel toward or from the work. This comprises a vertically extending screw-threaded rod G and a nut G' engaging the same. The nut is attached to the head E and the rod is rotatively mounted on the column F. A gear wheel H at the upper end of the screw-threaded rod is in mesh with a gear wheel H' on a parallel shaft H² which latter is adapted to be rotated by a hand wheel H³ at the front of the column through the medium of a horizontally extending shaft H⁴ and beveled gear wheels H⁵. Thus, the operator can raise or lower the grinder wheel D as required to place the same in operative relation to the work.

The mechanism above described may be used not only for the initial adjustment of the grinder wheel into operative relation to the work but also for manually feeding said grinder wheel into the work step by step. Where it is so used the screw-threaded rod G is held against axial movement and, consequently, will impart movement to the head E only, by its rotation in the nut G'. However, in the automatic feed the rod G is moved axially by a mechanism now to be described.

Automatic feeding mechanism

The rod G at its upper end is journaled in a bearing G² which permits axial as well as rotary movement of said rod. At its lower end it extends into a housing I mounted on the table C which housing also contains the mechanism for imparting axial movement to the rod. This mechanism includes a member J which is swiveled upon the rod by end thrust roller bearings J', J². These bearings prevent any relative axial movement between the rod G and the member J while permitting free relative rotation. The member J is axially slideable within a cylindrical bearing I' in the housing I and is provided centrally with a depending portion J³ which is connected by a wrist pin K with a bifurcated connecting rod member K'. The lower portion of the member

K' is apertured for the passage therethrough of a horizontal shaft L which is journaled in bearings M, M' within the housing I. The shaft L has an eccentric portion L' on which the member K' is mounted by radial and end thrust roller bearings K². Thus, the rotation of the shaft L in the bearings M and M' will through the eccentric L' and connecting rod member K' impart an axial movement to the member J and shaft G. Beyond the bearing M' the shaft L has a concentric portion L² on which is mounted a pinion N. The latter is in mesh with a rack member N' which has on opposite ends thereof piston portions N², N³ engaging hydraulic cylinders O and O' which are mounted on opposite sides of the casing I by bolts O². A further extension of the shaft L has fixedly mounted thereon a tripper P and adjacent thereto a rotatively adjustable tripper P'. These function to operate limit switches controlling the operation of hydraulic valves which will later be described. Finally at the end of the shaft L beyond the portion L² thereof there is mounted a radius arm Q.

Before further description of the apparatus, it may be stated that the feeding movement of the grinder wheel is effected by an axial movement of the screw-threaded rod G which, in turn, is accomplished by a rotation of the shaft L causing the eccentric portion L' thereof to move the connecting rod K' and member J. The rotation of the shaft L is accomplished by a movement of the pistons N² and N³ in the hydraulic cylinders O and O', which movement is controlled by admission of hydraulic fluid to one of said cylinders and expulsion of fluid from the other cylinder. Consequently, the amount of feeding movement must be controlled by accurately metering the fluid entering and leaving the cylinders O and O'.

Hydraulic operating system

Generally described the hydraulic operating system includes a source of hydraulic fluid under pressure, a valve controlling the admission of fluid alternatively to the cylinders O and O', a metering means connected to the cylinder O operating to successively eject predetermined volumes of fluid therefrom under pressure of fluid admitted to the cylinder O', and a valve controlling the successive operations of said metering means. More specifically, the system includes a tank R for the fluid, a pump R' operated by an electric motor R² for propelling the fluid from the tank through an outgoing conduit S and a relief valve R³ which returns the unused fluid to the tank while maintaining a predetermined constant pressure on the line S. The line S has a branch S' extending to the cylinder O' and a second branch S² leading to the metering device U. In the line S is an electromagnetically operated valve T and in the branch S², an electromagnetically operated valve T'. A conduit S^a extends from the cylinder O to the metering device and in this conduit is a normally closed and locked check valve V. The valve T normally opens the conduit S to maintain hydraulic pressure on the fluid in the cylinder O' but in another position of said valve, fluid is exhausted from the cylinder O' to be returned to the tank R while pressure fluid is supplied through a conduit S⁶ to the cylinder O. A check valve V' in this conduit prevents movement therethrough in the opposite direction. The valve T' normally opens the branch conduit S² to supply fluid through a portion S^b thereof to one end of the cylinder of the metering device U (as will be hereinafter explained), while

in another position of the valve T', the conduit portion S^b will be connected to an exhaust conduit S⁵ returning fluid to the tank. In the latter position of the valve T' the branch conduit S² is connected to a conduit S⁸ leading to the check valve V and functioning to unlock and open said valve. There is also a conduit S⁷ leading from the conduit portion S^a to the conduit S⁸ but containing a check valve V² which prevents movement of fluid therethrough in reverse direction. In the normal position of the valve T', both the conduits S⁷ and S⁸ are connected with the exhaust conduit S⁵.

Metering means

The metering means U is illustrated in Figs. 6 and 7 and comprises a cylinder U' containing a free piston U², the amplitude of movement of which is limited by an adjustable stop U³. This stop is preferably formed by a rod having a threaded portion U⁴ engaging a correspondingly threaded portion in a head U⁵ at one end of the cylinder U'. The conduit S^a connects with the end of the cylinder containing the stop U³, while the conduit S^b is connected to the opposite end of the cylinder. Thus, normally pressure fluid in the conduits S² and S⁶ holds the piston U² against the stop U³.

Locking check valve

The check valve V illustrated in Fig. 10 has a spring a for normally holding the valve seated. There is, however, a piston b in a cylinder c connected to the conduit S⁸, and this piston when actuated will press a rod d against said valve to unseat the same.

Operation

The operation of the hydraulic system as thus far described is as follows. Fluid under pressure fills both of the cylinders O and O' to press against the pistons N² and N³ therein and hold the rack member N' against movement. This stationary position of the parts is assured as the check valve V is locked from opening which prevents any escape of fluid from the cylinder O, while the cylinder O' is in open communication with the conduit S containing the pressure fluid. Assuming that the valve T' is operated, the valve T remaining in normal position, this will first connect the conduit S² with the conduit S⁸ thereby unseating the check valve V. Also, the conduit S^b will be connected to the exhaust conduit S⁵. Consequently, the piston U² is free to move in the cylinder U' under pressure of fluid expelled from the cylinder O and passing into the metering device through the conduit S^a and open check valve V. Such expulsion from the cylinder O is caused by the pressure of fluid in the cylinder O' which actuates the pistons N² and N³ and moves the rack N' a corresponding distance. If the valve T' is then restored to normal position, the valve V will be closed and locked and pressure fluid will enter the metering cylinder through the conduit S^b returning the piston U² to its position against the stop U³ and expelling fluid from the opposite side of said piston through the conduit S⁷ and check valve V² into the exhaust conduit S⁵. It is, therefore, apparent that each actuation of the valve T' will result in the expulsion of a measured volume of fluid from the cylinder O and a corresponding movement of the pistons N² and N³ and rack N'. The latter will actuate the pinion N which will rotate the shaft L causing the eccentric L' and connecting rod K' to

pull downward the member J and rod G. This will feed the grinder wheel into the work a predetermined amount and in successive operations of the valve T' the grinder wheel will be fed step by step to a predetermined limit. The valve T will then be operated (through control means hereinafter described) which will connect the cylinder O with the pressure line S² and the cylinder O' with the exhaust thereby returning the rack N' and the mechanism connected therewith to normal position.

Control mechanism

In the grinding of gears by formed grinder wheels as heretofore practiced, the relative reciprocation of the work and grinder wheel will move the latter through an interdental space of the gear to fashion the teeth on opposite sides thereof. In one method the gear is indexed after each reciprocation to register another interdental space with the grinder wheel and this is continued through a plurality of cycles until the finished size is attained. In another method the grinding of the teeth is completed at one point of registration before indexing to bring another pair of teeth in registration. Our improved automatic feed mechanism may be used with either method but preferably and, as specifically illustrated and described, the latter method is used. This has the advantage of expediting the work as it reduces the number of indexing operations to not more than the number of teeth.

The control mechanism, which is preferably employed, includes in addition to the hydraulic operating system previously described a plurality of electromagnetic limit switches and actuating members therefor. These are diagrammatically shown in Fig. 9 and, to avoid confusion, electrical connections are indicated in dotted lines. The table or carriage C is reciprocated by hydraulic means forming no part of the instant invention and, therefore, not illustrated in detail. However, it includes a reversible hydraulic valve 10 which is operated by a pair of dogs X and X' adjustably mounted on the table to determine the amplitude of reciprocation. The electromagnetically operated hydraulic valves T and T' are controlled by limit switches some of which are operated by the trippers P and P' and others by dogs on the reciprocating table. More specifically, the valve T' is operated by a pair of limit switches W and W' mounted on the bed A and a pair of cooperating dogs X² and X³ adjustably mounted on the table. These dogs are so positioned that after the grinder wheel has cleared the work at each end of the reciprocatory movement of the table one or the other of the dogs X² and X³ will operate its corresponding limit switch to energize the electromagnet or solenoid of said valve. At the beginning of the return stroke of the table the magnet is de-energized so that it remains energized for only a brief interval. The operation of the valve T is primarily controlled by the tripper P in conjunction with a limit switch W² operated thereby at a predetermined point in the rotation of the shaft L counterclockwise (Fig. 9). The closing of the limit switch W² energizes an electromagnet which withdraws the dog X so as to permit a further movement of the table C before reversing the same. As shown, the dog X is pivotally mounted in a housing member X⁴ (not indicated on Fig. 9) and is operated by a solenoid therein when the latter is energized. The member X⁴ also carries a dog X⁵ spaced from the dog X and performing a similar function when the

latter is withdrawn. In other words, it reverses the direction of travel of the carriage C after its longer movement. This reversal does not, however, immediately occur for the longer movement of the table causes the dog X² to operate a limit switch W⁴ which temporarily renders the reversing valve 10 inoperative so that the table remains stationary. There is also an adjacent limit switch W⁵ operated by the dog X² which starts in operation the indexing mechanism 11 (not shown in detail). Before the completion of the indexing operation a switch 12 is operated thereby to energize the solenoid of the valve T. This, as previously described, will connect the cylinder O with the pressure line S and the cylinder O' with the exhaust thereby actuating the rack N' in the reverse direction and rotating the shaft L clockwise back to its initial position. Finally, at the completion of this clockwise movement the tripper P' actuates the limit switch W³ which de-energizes the magnet of the valve T thereby completing the cycle.

Means for controlling the individual steps and total amount of the automatic feed

As previously described, the trippers P and P' are mounted on the shaft L. The tripper P is keyed in fixed position on the shaft but the tripper P' is rotatively adjustable. It is normally locked in its adjusted position by serrated adjacent faces on the members P and P' and a handled locking nut P³ engaging a threaded portion of the shaft. The member P' is also provided with a handle P⁴ so that by loosening the nut P³ the tripper P' may be drawn out of engagement with the tripper P and adjusted to be in the desired angular relation to the latter. Thus, the relative adjustment of the trippers P and P' determines the total angular adjustment of the shaft L and correspondingly the total depth that the grinder wheel will be automatically fed into the work. The tripper P is so located on the shaft L as to actuate the limit switch W² when the eccentric L' is at or near its lower dead center. The tripper P' is adjusted on the shaft L so that when the latter is turned to engage said tripper with the limit switch W³, the tripper P will be turned from its limit switch W² through a predetermined included angle. This determines the total feed of the grinder wheel from its initial to its final position. It will be obvious that the successive removal of equal volumes of fluid from the cylinder O by the metering device U will produce equal angular adjustments of the pinion N and shaft L but the vertical adjustment of the rod G will be varied. For instance, if the eccentric F' of the shaft F is in its initial position at 90° from the dead center, this will produce the maximum vertical movement of the rod G for a given volume of fluid and in successive steps the vertical adjustment will be progressively diminished. This produces a desirable effect in grinding as the finishing cuts should be less in depth than at the start. If, however, it is desired to change this ratio, it may be accomplished by the following means.

Adjustment of metering means

It has been previously stated that the volume of fluid withdrawn from the cylinder O by each operation of the metering device U may be varied by adjusting the position of the stop U³ for the piston U². This is preferably accomplished by providing a cap member U⁶ sleeved upon a member U⁷ on the head U⁵ and attached to the stop

rod U³. Therefore, a rotation of this cap will turn the rod U³ which by reason of its threaded engagement with the head U⁵ will move it axially within the cylinder U'. The cap may be calibrated to indicate the change in volume by such rotary adjustment.

Automatic adjustment of metering means

In addition to the manual adjustment for the metering means there is provided automatic operating adjustment means of the following construction. The portion of the rod U³ which projects beyond the cap U⁶ engages a bifurcated bearing U⁸ and between the furcations of this bearing a pinion U⁹ is mounted on said rod. A strap U¹⁰ embracing the pinion and pivoted on the rod extends upward therefrom and forms a bearing for a rack bar U¹¹ in mesh with said pinion. This rack bar extends to the radius arm Q previously described as attached to the end of the shaft L, said shaft and the rod U³ being mounted on the table parallel to each other. Q' is a pin having a head Q² slidably engageable with an undercut slot in the radius arm Q and clamped in different positions of adjustment by a nut Q³ engaging a threaded outer end portion of said pin. A sleeve Q⁴ on the pin between the nut Q³ and arm Q forms a pivot connection to the outer end of the rack bar U¹¹ so that by adjusting the pin Q' it may be placed at any desired radial distance from the center of the shaft L and preferably alternatively on opposite sides of said center. The rack U¹¹ may be disengaged from the pinion U⁹ by a handle U¹² threadedly engaging a bearing at the outer end of the strap U¹⁰ and having a swivel engagement with a coupling member U¹³. The latter has a finger U¹⁴ engaging a longitudinal channel in the rack bar so that said rack bar may be withdrawn from the pinion and reengaged with the same by manipulation of the handle U¹². This permits of making any desired adjustment of the pin Q' and also of arranging the radius arm U in any desired angular relation to the strap U¹⁰. Thus, the step by step rotation of the shaft L will communicate rotary movement to the stop rod U³ to change the length of free travel permitted to the piston. This will change the volume of fluid ejected from the cylinder O and correspondingly change the axial movement of the feed screw G.

What we claim as our invention is:

1. A feed mechanism comprising a nut connected with the member to be fed, a feed screw engaging said nut, means for manually rotating said screw, a member rotatable about an axis transverse to that of said screw and having an eccentric portion, a connection between said eccentric portion and said feed screw including a swivel permitting independent rotation of the latter while resisting independent axial movement thereof, a pinion on said rotatable member, a rack intermeshing with said pinion, a hydraulic cylinder and piston motor for actuating said rack, and fluid metering means associated with said hydraulic motor to operate the same successively step by step.

2. A feed mechanism comprising a nut connected with the member to be fed, a feed screw engaging said nut, means for manually rotating said screw, a member rotatable about an axis transverse to that of said screw and having an eccentric portion, a connection between said eccentric portion and said feed screw including a swivel permitting independent rotation of the latter while resisting independent axial move-

ment thereof, a pinion on said rotatable member, a rack intermeshing with said pinion, pistons at opposite ends of said rack, hydraulic cylinders with which said pistons are engaged, means for supplying fluid under pressure to one of said cylinders, and means for successively ejecting metered volumes of fluid from the other of said cylinders whereby said rack is actuated step by step to communicate a corresponding step by step movement to said feed screw.

3. A feed mechanism comprising a nut connected with the member to be fed, a feed screw engaging said nut, means for manually rotating said screw, a member rotatable about an axis transverse to that of said screw and having an eccentric portion, a connection between said eccentric portion and said feed screw including a swivel permitting independent rotation of the latter while resisting independent axial movement thereof, a pinion on said rotatable member, a rack intermeshing with said pinion, pistons at opposite ends of said rack, hydraulic cylinders with which said pistons are engaged, means for supplying fluid under pressure to one of said cylinders, means for successively ejecting metered volumes of fluid from the other of said cylinders whereby said rack is actuated step by step to communicate a corresponding step by step movement to said feed screw, and means for periodically reversing the direction of fluid in said cylinders to return said rack and feed screw to their initial positions.

4. In a grinding machine, the combination with a work holder, a grinder wheel and means for relatively reciprocating the same to effect the grinding of the work, of automatic means for relatively feeding said grinder wheel and work holder towards or from each other comprising a nut connected with the member to be fed, a feed screw engaging said nut, means for manually rotating said screw, a member rotatable about an axis transverse to that of said screw and having an eccentric portion, a connection between said eccentric portion and said feed screw including a swivel permitting independent rotation of the latter while resisting independent axial movement thereof, a pinion on said rotatable member, a rack intermeshing with said pinion, a hydraulic motor for actuating said rack alternatively in opposite directions, fluid metering means associated with said hydraulic motor to operate the latter successively step by step, and means operated by the relative reciprocation of said work holder and grinder wheel and between successive reversals thereof for actuating said metering means to feed said grinder wheel one step.

5. In a grinding machine, the combination with a work holder, a grinder wheel and means for relatively reciprocating the same to effect the grinding of the work, of automatic means for relatively feeding said grinder wheel and work holder towards or from each other comprising a nut connected with the member to be fed, a feed screw engaging said nut, means for manually rotating said screw, a member rotatable about an axis transverse to that of said screw and having an eccentric portion, a connection between said eccentric portion and said feed screw including a swivel permitting independent rotation of the latter while resisting independent axial movement thereof, a pinion on said rotatable member, a rack intermeshing with said pinion, a hydraulic motor for actuating said rack alternatively in opposite directions, fluid

metering means associated with said hydraulic motor to operate the latter successively step by step, means operated by the relative reciprocation of said work holder and grinder wheel and between successive reversals thereof for actuating said metering means to feed said grinder wheel one step, and means operating after a predetermined feeding movement of said grinder wheel for reversing said motor to return said wheel to its original position.

6. In a grinding machine, the combination with a work holder, a grinder wheel, means for relatively reciprocating the same to effect the grinding of the work and an indexing mechanism for said work holder, of automatic means for relatively feeding said grinder wheel and work holder towards or from each other comprising a nut connected with the member to be fed, a feed screw engaging said nut, means for manually rotating said screw, a member rotatable about an axis transverse to that of said screw and having an eccentric portion, a connection between said eccentric portion and said feed screw including a swivel permitting independent rotation of the latter while resisting independent axial movement thereof, a pinion on said rotatable member, a rack intermeshing with said pinion, a hydraulic motor for actuating said rack alternatively in opposite directions, fluid metering means associated with said hydraulic motor to operate the latter successively step by step, means operated by the relative reciprocation of said work holder and grinder wheel and between successive reversals thereof for actuating said metering means to feed said grinder wheel one step, means operating after a predetermined forwarding movement of said grinder wheel for stopping said reciprocation, operating said indexing mechanism and reversing said motor to return said grinder wheel to its original position, and means operated by the return of said grinder wheel for again reversing said motor and starting said reciprocation.

7. A feed mechanism comprising an axially movable member connected with the member to be fed, a member rotatable about an axis trans-

verse to that of said axially movable member and having an eccentric portion, a connection between said eccentric portion and said axially movable member, a pinion on said rotatable member, a rack intermeshing with said pinion, pistons at opposite ends of said rack, hydraulic cylinders with which said pistons are engaged, means for supplying fluid under pressure to one of said cylinders, and means for successively ejecting metered volumes from the other of said cylinders, whereby said rack is actuated step by step to communicate a corresponding step by step movement to said axially movable member.

8. A feed mechanism comprising an axially movable member connected with the member to be fed, a member rotatable about an axis transverse to that of said axially movable member and having an eccentric portion, a connection between said eccentric portion and said axially movable member, a pinion on said rotatable member, a rack intermeshing with said pinion, pistons at opposite ends of said rack, hydraulic cylinders with which said pistons are engaged, means for supplying fluid under pressure to one of said cylinders, means for successively ejecting metered volumes of fluid from the other of said cylinders whereby said rack is actuated step by step to communicate a corresponding step by step movement to said axially movable member, and means for periodically reversing the direction of fluid in said cylinders to return said rack and axially movable member to their initial positions.
